DUPLICATING MACHINE

Luis Mestre, New York, N. Y., assignor to Style Duplicator Corporation, New York, N. Y., a corporation of Delaware

Application August 14, 1939, Serial No. 290,103

6 Claims. (Cl. 101—118)

The invention herein described relates to a duplicating machine of the rotary type in which a perforated cylinder is employed, which cylinder is adapted to support a stencil sheet on its periphery and including means for rotating the cylinder to bring the surface of the stencil into contact with sheets of paper which are successively fed to the cylinder and between it and a pressure roll.

5 The invention has for its object to improve the control of the sheets as they are successively fed to the cylinder and pressure roll and to the accurate positioning of the sheets transversely of the cylinder.

10 Among the features by which these objects are attained, may be mentioned, the side guides which are not only independently adjustable to provide for sheets of different widths, but both 15 guides may be moved simultaneously to position the sheets at any desired location transversely of the cylinder. The usual rubber faced edge plates which control the paper as it is fed to the cylinder are in the present invention carried by the guides but are independently adjustable by a parallel motion, thereby providing better control of each sheet as it is being fed. An end plate enables the sheets to be accurately aligned at their top edges and while so aligned the entire 20 stack of sheets may be moved laterally to any desired location. Before the sheets are actually fed to the cylinder and pressure roll, the end plate is moved to a position where it does not interfere with the feeding of the sheets but serves 25 as a means to guide them between the cylinder and pressure roll. Means are also provided for preventing the cylinder from backward rotation and this preventing means is so related to the sheet feeding means that it is operative in any 30 adjusted position of the latter.

40 The various features and advantages will be better understood by the following detailed description and claims when taken in connection with the accompanying drawings in which:

45 Figure 1 is a perspective view of the duplicator showing its general construction;

Figure 2 is a section taken on the line 2—2 of Figure 1 and looking in the direction of the arrows; the figure being on a reduced scale;

50 Figure 3 is a detail of the mechanism for preventing backward rotation of the cylinder;

Figure 4 is a view of a portion of the machine viewed from underneath to show the connections whereby the side guides are moved;

55 Figure 5 is a part sectional, part elevational

view showing how the rubber faced edge plates are adjustable;

Figure 6 is a view of the same parts, but from a different viewpoint;

Figure 7 is a detail showing the adjustment for 5 the feed; and

Figure 8 is a section on the line 8—8 of Figure 7.

Referring to the drawings, Figures 1 and 2, the operative parts of the machine are supported by side frames each of which comprises a base member 2 having a flat upper face 4 and sloping side faces 5. Horizontal and vertical cross members 6 and 7 give the required rigidity to the frame 10 and the two frames are tied together by a U-shaped bar 8, a portion of which is shown in Figure 1. Supported by the side frames is a shaft 9 carrying a perforated stencil cylinder 10 adapted to be rotated by a handle 11 secured to its right hand end as shown in Figure 1. A pressure roller 12 carries end bearings 13, Figure 4, which bearings seat in notches in side plates 14, one of which plates is shown in Figure 2, the other plate being on the opposite side of the machine 15 and being of like construction. The frame formed by these side plates pivots about a shaft 16, which shaft is fastened to the frame. The end of the shaft adjacent the right hand frame plate 14, as viewed in Figure 2, is provided with 20 an arm 18 to which is attached one end of a spring 20. The other end of the spring is connected to a member 21 supported in a bracket 22 projecting from the right hand side frame 5 and a knurled knob 23 enables the tension of the 25 spring 20 to be varied thereby holding the pressure roller against the surface of the cylinder 30 with the desired degree of pressure.

It is to be understood that the frame comprising the side pieces 14, shaft 16 and arm 18, 40 pivots about the point 16. When it is desired to release the pressure roller from the cylinder, a knob 24, Figure 1 secured to shaft 25, Figure 2, is turned in a direction to cause the cam member 26 secured to shaft 25 to be moved to a vertical 45 position at which time it engages the frame and moves it down so that the pressure roller 12 is disengaged from the cylinder. A stop 28 normally limits the movement of the frame under tension of the spring 20 and this stop may be 50 adjusted.

For supporting the sheets of paper to be fed to the cylinder and pressure roll, a sheet delivery tray indicated generally by the reference character 30 is provided. Transverse slots 32 serve as 55

guideways for the side guides 33 for aligning the sheets along their side edges. A plate 34 pivoted at 35, Figure 2, serves as an aligning plate for the top edges of the sheets. The position of the plate 34, as shown in Figure 2, is the position to which it has been moved when it is desired to feed the sheets to the cylinder, but when the shaft 34 is rocked, as it may be through manipulation of the knob 36, Figure 1, the plate 34 is moved to a vertical position and the sheets are stacked against it.

The guides 33 are adjustable laterally to accommodate sheets of different widths and for this purpose levers 38 and 39 are provided. These levers are pivoted at 40 to the base of the machine as shown in Figure 4. Each lever is slotted near its upper end as shown in connection with the lever 38, the lever 39 being broken away at its upper part. A screw 41 passes loosely through each slot and into a block 42, each block being secured to a guide 33. The arm 39 is provided with a projecting lug 44 which is interiorly threaded for engagement with a screw thread 45 formed on a sleeve supported at 46 and by the side wall of the casing through which it passes. Its end is provided with a knob 48 by which the screw 45 may be rotated.

The arm 38 is likewise provided with a lug 44 with which engages a screw 49. The shank of this screw passes through the sleeve upon which the threads 45 are cut and it is also supported midway of its length at 50. The right hand end of the shank of the screw 49 is provided with a knob 52 by which the screw may be turned. The blocks 42 are each secured to one of the guides 33, therefore, when either of the knobs 48 or 52 are separately manipulated, the connected guide 33 will be moved laterally in the slot 32. The knobs 48 and 52, however, are not only concentrically mounted, but are so close together and are of such diameter that both may conveniently be manipulated together. Under these circumstances, therefore, the guides 33 will move as one and therefore move the sheets located between them to any position transversely of the cylinder. This feature makes it possible to change the width of the margin on the printed sheets with convenience and accuracy, since the sheets are aligned by the guides 33 and at the same time the aligning plate 34 serves to align the ends of the sheets. After the stack of sheets are ready to be fed, the plate 34 is moved to the position shown in Figure 2 and serves as a means to guide the sheets between the cylinder and pressure roll. Springs 53 may be provided to take up any lost motion of the screw threads.

The sheets are fed one at a time by feed rollers 54 carried by a frame 55 which is connected by an arm 56 to another frame 57 having side arm 58 pivoted at 60, Figure 2.

The frame 57 is rocked about the pivot 60 by a mechanism which will immediately be described, but before doing so it is desirable to point out that the feed rollers 54 are connected to their shaft by a one way clutch of any known construction whereby the rollers roll over the sheet with ease during the backward or non-feeding movement of the frame 57 but do not rotate on their axis when moved in the feeding direction. The rollers 54 being rubber faced, at this time exert sufficient friction on the sheet to feed it to the cylinder. This construction of the feed rollers in connection with the plate 34 permits the backward movement of the feeding frame and rollers 54 without disturbing the alignment of the sheets which has been brought about by the plate 34.

Continuing now with the description of the means for rocking the frame 57, at the right hand side of the machine, as viewed in Figure 2, there is a link 62 connected at 63 to the right hand arm 58. The other end of the link 62 is connected to a vertical link 64 pivoted at 65 to a lug extending from cross member 7, Figure 2. In order to vibrate the frame 57 to cause the sheets of paper to be successively fed to the cylinder, the link 64 is provided with a roller 66 engaging a circular groove in an eccentric 68. A plate 70 is connected to the eccentric, which plate is provided with an arcuate slot 71 adapted to be engaged by a pin 72 carried by the cylinder, as clearly shown in Figures 7 and 8. A winged nut 74 engages the end of the screw 72, to secure the plate 70 in any position of adjustment permitted by the slot 71 to thereby vary the throw of the link 64 by the eccentric 68.

To prevent the cylinder 16 from rotating backwardly to any harmful extent, the shaft 9 has secured to it a grooved roller 76, Figure 8. A pawl 78 pivoted at 79 to cross member 6 is adapted to engage the groove in the roller 76.

Referring now to Figure 3, the handle, as viewed in this figure, is adapted to be rotated in a clockwise direction. When so moved, the pawl 78 offers substantially no resistance to such movement. If, however, attempt is made to rotate the handle in reverse direction, then due to the action of the spring 80, the pawl would tend to move in a clockwise direction, Figure 3, but its length is such that it then tends to jam in the notch in the roller 76 and prevent any substantial backward movement of the handle.

It is to be observed that the action of the pawl 78 will prevent backward rotation of the handle with any adjustment of the plate 70 so that the feeding of the paper may start at different places during the rotation of the handle but the backward rotation is prevented regardless of the adjustment of the feed.

The side guides for the paper 33 are supplemented by rubber faced edge plates 82, Figures 5 and 6. While edge plates of this sort have heretofore been proposed, all of these as far as I am aware, are either separate from the guides 33 or if attached to them, they have been pivoted so that they move in an arc when adjusted. This method of mounting the edge plates is not desirable because the rubber does not bear equally throughout its length against the edge of a sheet of paper as it is fed to the machine. I propose to mount these rubber faced edge plates so that they are always adjusted in parallelism and to this end the guides 33 are cut away and a housing 84, Figures 5 and 6 permits sufficient movement of the plates 82 to give the necessary pressure against the side edges of the sheets as they are fed. The housing 84 is centrally bored and slotted and a screw 85 secured to each plate 82, passes through a collar 86 which is interiorly screw-threaded. A knurled knob 88 serves to rotate the collar 86 and thereby move the plate 82 parallel with itself within the limits necessary.

After the sheets have passed the cylinder and have been printed upon, they are received upon a delivery tray 90 as is customary. As shown, the front part of the tray 30 is hinged at 92, Figure 2, and the rear tray is likewise hinged at 93 whereby these trays may be folded up, but this feature forms no part of the present invention.

it having been fully described and claimed in my application filed of even date herewith.

What I claim is:

1. In a duplicating machine, the combination with a stencil cylinder and a pressure roll; of a sheet delivery tray from which sheets are fed to the cylinder and roll, side guides for aligning the sheets, a rubber faced edge plate mounted on each guide, means for moving said edge plates relatively to said guides and parallel to each other to different degrees to effect fine adjustment between said guides and plates, and means located at one side of the machine for moving both guides and edge plates together transversely of the tray while maintaining the relative fine adjustment of the guides and edge plates. 5
2. In a duplicating machine, the combination with a stencil cylinder and a pressure roll; of a sheet delivery tray from which sheets are fed to the cylinder and roll, side guides for aligning the sheets, means for moving each guide transversely of the tray independently of the other guide, said moving means for each guide being concentrically located so that both may be manipulated by one hand of the operator to thereby move both guides simultaneously to the same degree. 10
3. In a duplicating machine, the combination with a stencil cylinder and a pressure roll; of a sheet delivery tray from which sheets are fed to the cylinder and roll, side guides for aligning the sheets, means including a screw one for each guide for moving a guide transversely of the trays independently of the other guide, one of said screws being housed within the other, and means located at one side of the machine for moving both screws. 15
4. In a duplicating machine, the combination with a casing and a stencil cylinder supported thereby; of a sheet delivery tray from which sheets are fed to the cylinder, side guides for aligning the sheets, means including a screw one for each guide for moving a guide transversely of the trays independently of the other guide, one of said screws being housed within the other, and means located at one side of the machine for moving both screws. 20
5. In a duplication machine, the combination with a stencil cylinder and a pressure roll; of a sheet delivery tray from which sheets are fed to the cylinder and roll, side guides for aligning the sheets, said guides having a cut-out portion intermediate their ends, a housing secured to each guide and bridging said cut-out portion, the outer wall of said housing being parallel to the guide to which the housing is secured, a rubber faced edge plate mounted in each housing and means cooperating with each housing for moving each edge plate relatively to said guides and parallel to each other to different degrees to effect fine adjustment between said guides and plates. 25
6. In a duplication machine having a printing cylinder and a pressure roll; a sheet delivery tray from which sheets are fed to the cylinder and roll, side guides for aligning the sheets, said guides having a cut-out portion intermediate their ends, 30 a housing secured to each guide and bridging said cut-out portion, the outer wall of said housing being parallel to the guide to which the housing is secured, a rubber faced edge plate mounted in each housing and means cooperating with each housing for moving each edge plate relatively to said guides and parallel to each other to different degrees to effect fine adjustment between said guides and plates. 35

LUIS MESTRE. 40
